SHOE CONSTRUCTION

Charles Leo Daly, Belmont, Mass., assignor to
 Daly Bros. Shoe Co. Inc., Boston, Mass., a cor-
 poration of Massachusetts

Application September 22, 1937, Serial No. 165,135

5 Claims. (Cl. 36—14)

This invention relates to shoe construction, and particularly to an inexpensive work shoe.

Such shoes are sold in a highly competitive market and manufacturers are constantly seeking to reduce costs by effecting economies in materials and manufacturing operations.

As a result, this type of shoe has become substantially standardized as to its construction and materials. Generally it is a nailed shoe with a 10 rubber outsole, leather midsole and a so-called "tuck" shank of leather or imitation leather stapled therein, although sometimes the tuck shank is of horn fibre cemented or otherwise fastened in place.

15 The use of either the stapled tuck shank or the horn fibre shank involves an extra operation which adds to the cost of the shoe. Neither type of shank, moreover, is entirely satisfactory, due to its tendency to swell up and work loose when 20 the shoe is wetted in service.

Broadly, the object of my present invention is to produce a shoe of this general type which can be manufactured at a substantial saving over present methods and which will be superior in 25 point of appearance, comfort and serviceability to shoes now on the market.

In attaining this object, I provide a composite or multi-layer outsole of vulcanized rubber, comprising an outer or wear layer and a top or inner layer. The outer layer is of substantial thickness and is preferably of conventional black rubber color. The top or inner layer extends over 30 only the heel and shank portions of the outsole, terminating in the region of the rear edge of the conventional midsole. It is generally colored tan in simulation of the midsole of which optically it appears to be a continuation in the finished shoe, being of approximately the same thickness as the midsole, and preferably also 35 being so contoured as to provide an included pocket for the reception of a conventional shank stiffener.

The outsole may be full length or three-quarter length. If of full length it may be molded in the 40 region of the heel piece of the shoe to provide either an inner layer which simulates in thickness and color the conventional leather heel piece of the shoe or the inner layer may terminate at this point and the outer layer itself may be 45 thickened to provide a heel piece portion substantially of the same thickness as the conventional leather heel piece, in which latter event, however, such thickened heel piece portion might or might not be colored to simulate leather. If 50 of three-quarter length, the outer layer may ter-

minate in the region of the conventional leather heel piece and the inner layer may be extended rearwardly to provide a heel piece portion simulating in thickness and color the conventional leather heel piece. Such three-quarter sole is 5 particularly useful with a cupped rubber heel such as disclosed in my prior Patent No. 2,025,647, of December 24, 1935.

My invention avoids the necessity of cutting the leather tuck shank to shape, skiving at both 10 ends, and stapling or otherwise fastening it to the outsole, while at the same time retaining the optical effect of the leather tuck shank. Being molded as an integral part of the outsole the shank-forming portions of the inner layer are 15 permanent and there is no problem of their becoming loose or distorted when the shoe is wetted in service.

In the accompanying drawing:

Fig. 1 is a perspective view of a conventional work shoe equipped with a full length outsole in accordance with my invention.

Fig. 2 is a perspective view of such outsole removed.

Fig. 3 is a fragmentary cross section on approximately the line 3—3, of Fig. 1.

Fig. 4 is a perspective view showing a modified outsole, and

Fig. 5 is a perspective view showing a still further modification of the outsole, the same being especially adapted for use with a cupped rubber heel such as shown in the Daly patent aforesaid.

I have indicated generally at 10 a shoe of the work shoe type constructed of the usual upper materials 11, and equipped with conventional insole 12, midsole 14, and heel tap 15 of rubber or leather, as desired. These parts are assembled in the usual manner with my novel outsole indicated generally at 16.

The outsole is of composite or multi-layer molded rubber construction and may be either full length as shown in Figs. 1, 2 and 4, or three-quarter length as shown in Fig. 5. It consists of a bottom or wear layer 17 of conventional thickness, and a relatively thin top or inner layer 18 of different optical characteristics. Preferably, but not necessarily, the bottom layer is colored or scuffed to show the conventional black of rubber, and preferably the upper layer is colored tan in simulation of leather.

As shown in Figs. 1, 2 and 4 the inner layer 18 extends over the rear and shank portions only of the bottom layer 17, terminating in the region of the rearwardly skived rear edge of the mid-

sole. In the region of the shank the marginal portions 19 of the inner layer 18 constitute a built-up tuck shank as well as defining an included pocket 20 for the reception of a conventional shank stiffener. The marginal portions 19 are co-planar with the heel base portion 21 of the inner layer 18 if the outsole is a full sole as illustrated in Fig. 2. At their forward ends said marginal portions 19 of the inner layer 18 are forwardly beveled as at 22 and merge with the bottom layer 17 of the outsole.

In a completed shoe having the outsole of Fig. 2, the rearwardly beveled end of the leather midsole 14 overlaps and matches perfectly with the forwardly inclined portions 22 of the marginal portions 19 of the inner layer 18 of such outsole, exhibiting no perceptible break or line of demarcation, and said marginal portions 19 and the heel base portion 21 optically extend as continuations of the midsole, and being of substantially the same thickness and color as said midsole give the effect of an all leather edge completely around the shoe.

In the modification of Fig. 4, the outsole is also of full length, but the inner layer 18 terminates in the region of the heel piece of the shoe and the outer layer 17 is thickened as at 24 to provide a heel piece section of equivalent thickness to the conventional leather heel piece of the shoe. This thickened section 24 may be colored to simulate leather, if desired, but ordinarily is left in its natural black or dark color.

Where, as in Fig. 5, a three-quarter outsole 25 and a cupped heel 26 of the type disclosed in the Daly patent aforesaid is used, the rear or cut end of the bottom layer 17 is preferably rearwardly beveled as indicated at 27 to fit within the depressed shelf area of the cupped heel, the inner layer 18 of the outsole extending as a heel piece portion 28 which simulates in color and thickness the usual leather heel piece of the shoe, and in this respect also simulating the heel base portion 21 of the full outsole shown in Fig. 2.

Various other modifications in construction and materials may obviously be resorted to within the

spirit and scope of my invention as defined by the appended claims.

What I therefore claim and desire to secure by Letters Patent is:—

1. A shoe, comprising upper materials, a heel, 5 a midsole, and a composite rubber outsole including an outer or wear layer of substantial thickness and an inner layer of reduced thickness and contrasting color extending forwardly over the rear portion of the outsole and terminating at substantially the rear edge of the midsole, said inner layer presenting in the shank region of the shoe marginal edges which in color and thickness give the optical effect of being continuations of the midsole. 10

2. The shoe of claim 1, the inner layer of the outsole extending as a heel base portion which is substantially co-planar with said marginal edges and in the heel base area of the shoe gives the optical effect of the conventional leather heel 15 piece.

3. The shoe of claim 1, the marginal edges of the inner layer of the outsole being forwardly beveled at their juncture with the midsole.

4. The shoe of claim 1, the marginal edges 25 of the inner layer of the outsole defining with each other an included pocket for the reception of a shank stiffener.

5. A shoe, comprising upper materials, a midsole, and a cupped heel, and a composite rubber outsole including an outer layer of three-quarter length and of substantial thickness and an inner layer of reduced thickness and contrasting color extending forwardly over the rear portion of the outsole and terminating at substantially the rear edge of the midsole, said inner layer presenting in the shank region of the shoe marginal edges which in color and thickness give the optical effect of being continuations of the midsole, and the rear portion of said inner layer extending as 35 a heel base portion which is substantially co-planar with said marginal edges and in the heel base area of the shoe gives the optical effect of the conventional heel piece. 40
